UNITED STATES PATENT OFFICE.

JOHN HOPKINSON, OF WESTMINSTER, COUNTY OF MIDDLESEX, ENGLAND.

CONDUCTOR FOR ELECTRIC RAILWAYS.

SPECIFICATION forming part of Letters Patent No. 325,083, dated August 25, 1885.

Application filed March 9, 1885. (No model.) Patented in England December 8, 1884, No. 16,128.

To all whom it may concern:

Be it known that I, JOHN HOPKINSON, F. R. S., a subject of the Queen of Great Britain and Ireland, and residing at 4 Westminster Chambers, Westminster, in the county of Middlesex, England, have invented certain Improvements in Electrical Railways and Tramways, (for which I have made application for a patent in Great Britain, No. 16,128, dated December 8, 1884,) of which the following is a specification.

My invention relates to an improved means of making the electrical connection between the generator and the motor in an electrical railway or tramway of that class in which a wire or wires is suspended above the track, a contact-piece on the car rolling or rubbing against the wire.

My invention consists in extending the contact pieces or rollers on the cars transversely to the car, so that the suspended conductor may occupy any position over the car laterally and contact still be maintained.

It also consists in placing the contact-pieces on the cars at such a level that they will pass clear beneath the supports of the suspended wire without touching the same or lifting the wire from them.

The advantages of the overhead wire are, among others, that the conductor is placed out of reach and that minutely-accurate adjustment is not needed, as the contact-piece on the car may lift the wires as the car travels along by nearly the full amount of the sag of the wire.

The peculiar advantages of my present invention are, that the distances between posts may be considerable, even on curves in the line, owing to the great freedom which arises from the lateral extension of the contacts on the car; also, that since the contacts pass clear of the insulating supports, these latter may be of a simple and inexpensive construction. The lateral extension of the contacts facilitates the working of junctions as well as of curves.

Referring to the drawings, Figure 1 shows a side elevation of the conductor and car when the car is between two posts. Fig. 2 is a similar view showing the car passing a post. Fig. 3 is an end elevation. Fig. 4 is a side view of

a modified arrangement of line-wires, and Figs. 5 and 6 are diagram plan views illustrating how my improvement comes into practical use.

The conducting-wire *a a* is carried much as telegraph-wires are carried; but special provision is made against the varying tension of the wires which arises from the passing cars lifting the wires above it. This may of course be effected by using posts fixed with exceptional strength; but when the spans are approximately equal it may be effected by allowing the wires to be free to slide longitudinally when they are supported by the posts.

b b are the contact-pieces, extending across the width of the car and fixed in the case shown at a considerable height overhead, in order to be out of reach of passengers on the top of the car, and to leave headway under the wires where other roads cross. Where these conditions do not exist, both conductors and contact-pieces may be placed lower. It will be observed that at least two contact-pieces are placed on the car, to enable the contact to be maintained when the car is passing a post, and this is necessary in my system, as the contact-bars are at a lower level than the supports of the suspended wires.

The contact-bars *b b* may be replaced by rollers to avoid friction and wear and tear; but in a similar way the rollers must be extended across the car to make contact at any point of its width.

I prefer to use at least two wires as the conductor, in order to secure continuous contact even when the wires vibrate, and it is better to stretch them with a slightly-different tension, so that their normal times of vibration may be different. Where great uniformity of contact is required, the number of posts is increased and the wires are hung from alternate posts, as shown in Fig. 4.

It will be readily understood that a separate and similarly-insulated return-conductor may be provided; but I prefer to use the rails and the earth as return, as is well known. In that case the generating-dynamo has one pole connected to the earth, the other to the insulated conductor *a a*, while the contacts *b b* are connected by a wire or other conductor to one pole

of the dynamo placed on the car, the other pole of which is connected electrically to the wheels of the car and so to earth.

The electrical circuit is thus: generating-
5 dynamo, conductor *a a*, contacts *b b*, motor-
dynamo, wheels of car, rails, earth, generat-
ing-dynamo.

Fig. 5 illustrates the application of my sys-
tem to a curve. It will be observed that at X
10 the bar *b b* makes contact near one extremity,
whereas at X^2 it makes contact at the other
extremity, but that the wires are not displaced
laterally.

Fig. 6 illustrates the application to a junc-
15 tion of two lines. In this case, also, the lateral
extension of the contact *b* and its being placed
at a lower level than the supports of the wire
enable the connection to be readily maintained
at the junction.

20 It is unnecessary to describe or show the ar-
rangement of the dynamo on the car or the
mechanisms for making or reversing the con-
nections thereof.

I claim as my invention—

1. The combination of the suspended con-
ductor or conductors *a a* with the car carrying
the contact bars or rollers *b b*, fixed to the car
at such a level as to pass clear beneath the in-
sulating supports *c c*, and extending trans-
versely across the car.

30 2. In electric tramways or railways, the com-
bination of the suspended conductor or con-
ductors with the car having a contact piece or
surface or contact pieces or surfaces extended
across the car, so that in all positions of the 35
car proper contact with the wires of the line
is maintained, substantially as hereinbefore
described.

In testimony whereof I have signed my name
to this specification in the presence of two sub- 40
scribing witnesses.

JOHN HOPKINSON.
